UNITED STATES PATENT OFFICE.

MARVIN O. ROYCE AND JOHN CONNOLLY, OF SOMERVILLE, MASSACHUSETTS.

HOISTING APPARATUS.

SPECIFICATION forming part of Letters Patent No. 434,001, dated August 12, 1890.

Application filed March 29, 1890. Serial No. 345,866. (No model.)

To all whom it may concern:

Be it known that we, MARVIN O. ROYCE and JOHN CONNOLLY, both of Somerville, county of Middlesex, State of Massachusetts, 5 have invented an Improvement in Hoisting Apparatus, of which the following description, in connection with the accompanying drawings, is a specification, like letters on the drawings representing like parts.

10 This invention has for its object to construct a hoisting apparatus and support for a swing-staging or other device, whereby the staging may be held by means independent of the building. For swing-staging a separate hoisting device is located at each end thereof, yet for many purposes but a single hoisting device is necessary. When two hoisting devices are employed, they are made substantially alike. The hoisting device consists of a main frame and a riser or arm arranged to slide telescopically therein or parallel therewith to extend the main frame in the direction of its length; also, means for lifting the riser and for holding it in any desired position, and also means for supporting the main frame in elevated position and for assisting in raising the said frame into such elevated position. The hoisting device will bear a suitable pulley-block at its upper end, 25 from which a staging or other device may be suspended. When the hoisting device is not in use, the riser may be lowered to shorten up the device, and the main frame-support may be closed upon the parts for compactness. We have provided suitable brackets, 30 which may be attached to the side of a building for additional support for the swing-staging.

Our invention comprehends the use of an elevator car or basket to be supported by the hoisting device herein described, it being raised and lowered by any suitable means.

Figure 1 shows in front elevation a hoisting apparatus embodying this invention, it being shown in connection with a swing-staging, and hence two hoisting devices are employed; Fig. 2, a side elevation of the hoisting apparatus shown in Fig. 1, the riser or telescopically-moving arm being lowered 45 to save space on the drawings, and the bracket being secured to the side of the building,

which may serve as an additional support for the staging; Fig. 3, a detail of the bracket; Fig. 4, a side view of a single hoisting apparatus arranged to support the elevator car or basket; Fig. 5, a detail of the elevator car or basket, and Fig. 6 an edge view of one of the hoisting devices with the parts arranged in position for conveyance or storage.

The hoisting apparatus herein shown consists of two hoisting devices substantially alike, so one only will be described.

The hoisting device comprises, essentially, a main frame *a*, hollow or tubular, and a riser or telescopically-movable arm *b* of suitable 65 size to enter and move freely within the main frame *a*.

The means herein shown for raising the riser or telescopically-movable arm *b* consists of a cord or chain *c*, one end of which is rigidly attached to the frame *a* at 2, it extending around a pulley *b'*, (see dotted lines, Fig. 2,) carried by the riser *b* at its lower end, thence around a pulley *b*², journaled in a bracket or arm attached to the main frame *a*, 75 and thence around a suitable winch *w*, which may be turned by a crank and locked in any desired position. It will be seen that the point of attachment—namely, at 2—of the cord *c* is directly opposite the pulley *b*², or 80 nearly so, and the cord is carried down into the tubular main frame *a* by means of the riser *b*, when the latter is lowered, and by pulling upon the cord *c* the riser will be lifted, the locking device *w'* on the winch *w* holding 85 it at any desired point. The riser or arm *b* bears a pulley-block *b*⁴, over which a cord *d*, supporting the staging *d'*, passes, said cord being secured at the bottom of the main frame by winding it on a cleat *w*². By operating 90 the cord *d* in any usual manner the staging *d'* can be raised and lowered at will.

We have arranged brackets *e*, which may be bolted to the side of a building to give additional support to the staging *d'*, these brackets being preferably formed of metal by bending a strip or bar of steel into proper shape. A yoke *f* is secured to the upper end of the riser *b*, which bearing against the building keeps the staging *d'* away from the side wall 100 of the building a proper distance. This yoke may, if desired, be provided with any suit-

able friction-roller. The lower end of the main frame *a* is made conical or pointed, as at *g*, to enter the ground.

A suitable support is provided for the main

- 5 frame, it consisting, as herein shown, of two legs *n n'*, connected at their upper ends to strong spiral springs *n²*, they being spread at their lower ends and connected by means of a cross-bar *n³*. The tendency of the springs 10 is to draw the main frame *a* toward the support *n n' n³* in the direction of the arrow, Fig. 2, and a cross-bar *n⁴* is secured to the said main frame *a*, which limits its movement.

When it is desired to fold the apparatus in 15 compact form for shipment or for conveyance, or for storage when not in use, the support *n n' n³* is turned up toward the riser against the tension of the springs, and the cross-bar *n³* passes over the upper end of the 20 riser or arm *b*, after which the said riser or arm is pushed outward sufficiently to resist the return movement of the said support, the cross-bar *n³* bearing against it, as shown in Fig. 6.

25 When it is desired to lift the device, the riser or arm *b* is withdrawn, the support will be immediately released, and the outer end of the support bearing on the ground will, by means of the strong springs *n² n²*, draw the 30 foot of the main frame toward the inner end of the support, lifting the upper end of said frame into its elevated position, the foot of the support *n n' n³* being held from slipping by the operator. This support, being thus 35 held and the device being raised by the springs *n² n²*, causes the upper end of the riser to follow substantially in a vertical line.

It will be seen that many of the parts thus far described may be changed in detail, yet 40 come within the spirit and scope of this invention.

45 In Fig. 4 a single hoisting device is employed, it being desired to lift an elevator car or basket or equivalent *e²*, such a car being shown in Fig. 5. The hoisting device is in this instance substantially the same as before referred to. The car, however, has a loop or eye *t*, through which its supporting - cord passes to prevent it from swinging too freely.

50 The hoisting device herein described may

be used for many purposes, so we do not desire to limit our invention to any particular purpose.

We claim—

1. In a hoisting device, a tubular main 55 frame *a* and telescopically - movable arm *b* therein, combined with an operating - cord passing over the lower end of the said arm *b* within said frame, substantially as described.

2. In a hoisting device, a tubular main frame 60 *a* and an arm *b*, combined with an operating-cord passing over the lower end of arm *b*, over pulley *b²* on the frame to a winch *w*, and a locking device *w'* for holding said arm in any desired position, substantially as described. 65

3. In a hoisting device, the main frame *a*, an arm *b*, and means for moving the arm, combined with a support for the device pivoted to the main frame and spring-controlled at its pivotal point, substantially as described. 70

4. In a hoisting device, the main frame and arm movable parallel therewith and with a yoke *f*, combined with means for moving the said arm, a pivoted support for maintaining the main frame in elevated position, and a 75 spring connecting said frame and support, substantially as described.

5. In a hoisting device, the main frame and arm movable parallel therewith and bearing a pulley-block, combined with means for moving the arm, and a spring-controlled support pivoted to the upper end of and normally drawn toward the main frame for lifting and thereafter supporting the said main frame, substantially as described. 85

6. In a hoisting device, the main frame and arm movable parallel therewith and means for moving the arm, combined with the spring-controlled support *n n' n³*, pivoted to the main frame, and a stop *n⁴* for said support, 90 substantially as described.

In testimony whereof we have signed our names to this specification in the presence of two subscribing witnesses.

MARVIN O. ROYCE.
JOHN CONNOLLY.
